UNITED STATES PATENT OFFICE.

GEORGE STEPHEN SUMMERS, OF GORDONVILLE, MISSOURI.

CHICKEN-BROODER.

No. 823,902.

Specification of Letters Patent.

Patented June 19, 1906.

Application filed April 20, 1906. Serial No. 312,878.

To all whom it may concern:

Be it known that I, GEORGE STEPHEN SUMMERS, a citizen of the United States, residing at Gordonville, in the county of Cape Girardeau and State of Missouri, have invented 5 certain new and useful Improvements in Chicken-Brooders; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in chicken-brooders, and comprises a simple and efficient means whereby pure air is heated and passed into the brooding-chamber and afterward utilized with its 20 impurities for feeding the lamp and afterward passing to the atmosphere through a suitable passage-way.

More specifically, the present invention 25 comprises a brooder having two compartments, one of which contains a heating apparatus and the other provided with a double floor with passage-ways underneath the same which communicate with the brooding-chamber, thus forming circuitous passage-ways 30 through which the foul air from the brooding-chamber may be conducted to the lamp-chamber.

The invention consists in various other details of construction and combinations and 35 arrangements of parts, which will be herein-after fully described and then specifically defined in the appended claims.

I illustrate my invention in the accompanying drawings, in which—

40 Figure 1 is a vertical sectional view through my improved brooder. Fig. 2 is a cross-sectional view on line 2 2 of Fig. 1. Fig. 3 is a sectional view on line 3 3 of Fig. 1, showing a top elevation of the upper floor of the brood-45 ing-chamber; and Fig. 4 is a sectional view on line 4 4 of Fig. 1.

Reference now being had to the details of the drawings by letter, A designates the outer casing of the brooder, which is provided with 50 the door A' in one end leading to the brooding-chamber and a door A² at the opposite end which leads into the heating-chamber. The interior of the brooding-chamber is divided by a vertical partition B, separating 55 the brooding-chamber C from the lamp-chamber D. Said brooder has two floors, (desig-

nated in the drawings by letters E and F,) which are spaced apart. The vertical partitions G divide the space beneath the floor F into three longitudinal compartments H, H', and H², one of which compartments H' communicates, through a passage-way K, with the lamp-chamber. Said partitions, which extend forward from the lamp-chamber, terminate a short distance from the end of the 65 brooder, forming a communicating space about the ends of said partitions with the several compartments H, H', and H². The floor F is provided with vent-holes N, which afford communication between the brooding-70 chamber above the floor and the compartments H and H². Said holes are screened with fine wire, which will permit the passage of air therethrough, but prevent dirt or other foreign matter from being scratched into the 75 holes by the chicks, and thus filling the same up.

Positioned within the brooder and extending through the partition dividing the same from the lamp-chamber is a heating drum or 80 chamber O, which is positioned adjacent to the roof of the brooder and set at an inclination, the portion which extends into the lamp-chamber being lower than the opposite end, thereby allowing the heat to pass readily 85 through the same. Leading from the inner end of the heating drum or chamber and from the under portion thereof is a pipe O', which turns at a right angle at O² and having a horizontally-disposed portion extending 90 nearly to the end of the brooder, thence turns upwardly at right angles and makes exit through the roof of the brooder.

J designates a pipe leading downward from the lower end of the heating drum or chamber and which is adapted to fit over the chimney of a lamp or burner, and I designates a pipe which is positioned within the lamp-chamber and has one end opening through the adjacent end of the casing, preferably 100 upon a level with the opening into the pipe which fits over the lamp, and said pipe I passes through the closed end of the heating drum or chamber which is within the lamp-chamber and extending the entire length of 105 the heating-drum opens at the opposite end thereof into the brooding-chamber. It will thus be noted that the pipe I as it passes through the upper portion of the heating-drum and longitudinal therewith will be subjected 110 the entire length of the drum to the heat from the lamp, thus heating the fresh air

before it makes exit into the brooding-chamber. It will be noted that said partition B, which divides the lamp-chamber from the brooding-chamber, has an opening B' in the 5 bottom of the partition whereby communication may be had between the brooding and lamp chambers. The roof of the brooder is provided with suitable doors S, and a sight-aperture T is formed in the end of the casing 10 whereby the flame of the lamp may be visible from the outside.

From the foregoing it will be noted that the lamp-chamber is tightly inclosed, there being no opening from the latter to the atmosphere excepting through the medium of 15 the door, which is adapted to fit closely with mitered joints, and the only oxygen for supporting combustion in the lamp is drawn from the brooding-chamber through the circuitous 20 passage-way shown and described. The fresh air is drawn through the pipe I, the opening to which pipe is on a level with the bottom of the pipe which fits over the lamp, and by natural laws the flow of pure air is established. 25 The hot air being lighter than the cold, the heater is most intensely heated at the point where the fresh air enters the heating drum or compartment. As the opposite or inner end of the heating-compartment 30 is slightly elevated, the upward and forward movement of pure warm air is established. As the air traverses the length of the heating-drum it is gradually warmed by the heat surrounding the pipe, and when it reaches 35 the open end it will flow into the brooding-chamber among the chicks, thereby affording a constant radiation of pure wholesome air. The products of combustion which pass through the heating-drum are caused to be 40 deflected downward through the angled pipe before making exit through the upright portion of the pipe, thereby utilizing to the fullest extent the heat before it escapes to the atmosphere. The vitiated or foul air within 45 the brooder being utilized for purposes of combustion in the lamp, it will be drawn by the draft established in the direction indicated by arrows in the drawings, said foul air passing down through the openings N, thence 50 through the passage-ways H and about the partitions G, back through the central passage-way H and opening K into the lamp-chamber. By this method of heating the pure warm air is thoroughly distributed 55 through the brooder and all of the heat comes from above, the foul air, which contains carbonic-acid gas, being carried by a constant draft out of the brooding-chamber. The constant movement of air from the brooding-chamber as it passes under the upper floor to 60 the lamp-chamber slightly warms the floor, making it pleasant for the chicks under foot as well as overhead, the floor not being made sufficiently warm to cause leg weakness. 65 The perfect system of ventilation under the

floor keeps the latter perfectly dry, and there is absolutely no foul vapor rising from the floor to contaminate the pure air therein. By the provision of a brooder made in accordance with my invention the same may 70 be tightly closed up in cold weather, and the chicks will have as much pure air as if in the open atmosphere. It will also be noted that the chance of impure air entering the brooder is absolutely impossible. 75

What I claim is —

1. A chicken-brooder comprising a casing divided by a partition into lamp and brooding chambers, a double floor within said brooding-chamber with the space between the floors divided into longitudinal communicating passage-ways, one of which communicates with the lamp-chamber and the others with the brooding-chamber, a heating-drum passing through said partition, a lamp-pipe leading to said heating-drum, a fresh-air pipe leading through the end of the casing passing through the lamp-chamber and said heating-drum, making exit into the brooding-chamber, as set forth. 80

2. A chicken-brooder comprising a casing divided by a partition into lamp and brooding chambers, a double floor within said brooding-chamber, longitudinal partitions mounted in the space between the floors and terminating a slight distance from the end of the brooder, thus dividing said space into longitudinal passage-ways in communication with one another, the upper floor having openings adjacent to the partition dividing the lamp-chamber from the brooding-chamber, and the central one of said passage-ways between the floors communicating with the lamp-chamber, a heating-drum passing through the partition between the two chambers, a lamp-pipe leading into said drum, and a fresh-air pipe leading through the end of the casing and passing through said drum, and opening at its inner end into the brooding-chamber, as set forth. 95

3. A chicken-brooder comprising a casing divided by a partition into lamp and brooding chambers, a double floor within said brooding-chamber with the space between the floors divided into longitudinal communicating passage-ways, one of which communicates with the lamp-chamber and the others with the brooding-chamber, a heating-drum passing through the chambers and set at an inclination, a lamp-pipe leading into said drum, and a fresh-air pipe opening through one end of the casing and having an inlet end on a level with the opening into the lamp-pipe and passing longitudinally through the heating-drum into the brooding-chamber, as set forth. 105

4. A chicken-brooder comprising a casing divided by a partition into lamp and brooding chambers, a double floor within said brooding-chamber with the space between 110

the floors divided into longitudinal communicating passage-ways, one of which communicates with the lamp-chamber and the others with the brooding-chamber, a heating-
5 drum passing through the chambers and set at an inclination, a lamp-pipe leading into said drum, a fresh-air pipe opening through one end of the casing and having an inlet end on a level with the opening into the lamp-
10 pipe and passing longitudinally through the heating-drum into the brooding-chamber,

and an exit-pipe for the products of combustion leading downwardly from the under side of the inner end of the heating-drum, thence upwardly turned and passing through the 15 top of the brooder, as set forth.

In testimony whereof I hereunto affix my signature in the presence of two witnesses.

GEORGE STEPHEN SUMMERS.
